UNITED STATES PATENT OFFICE.

PETER H. SAGER, OF MARIANNA, FLORIDA.

FLUSHING AND COVER-OPERATING MECHANISM FOR TOILETS.

1,313,740.

Specification of Letters Patent.

Patented Aug. 19, 1919.

Application filed March 15, 1918. Serial No. 222,670.

To all whom it may concern:

Be it known that I, PETER H. SAGER, a citizen of the United States, residing at Marianna, in the county of Jackson and 5 State of Florida, have invented certain new and useful Improvements in Flushing and Cover-Operating Mechanisms for Toilets; and I do hereby declare the following to be 10 a full, clear, and exact description of the invention, such as will enable others skilled in the art to which it appertains to make and use the same.

This invention relates to a manually operated mechanism for raising the cover of 15 ordinary water closets or toilet bowls and for lowering the cover and flushing the bowl simultaneously with the lowering of the seat cover.

More specifically, the invention comprehends the provision of a pivotally mounted 20 manually operated lever which is connected, through the medium of a bar, to the seat cover of an ordinary water closet or toilet bowl, which lever engages and idly operates 25 a pivoted pawl upon the raising action of the cover of the bowl and strikes and operates the pawl in a movement which lowers the cover of the bowl for operating the flushing mechanism to flush the bowl simultaneously with the lowering of the cover thereof. 30

With the foregoing and other objects in view, this invention consists in such novel features of construction, combination and arrangement of parts as will be hereinafter 35 more fully described, illustrated in the accompanying drawings and claimed.

In describing the invention in detail, reference will be had to the accompanying drawings, wherein like characters designate 40 like and corresponding parts throughout the several views, and in which:

Figure 1 is a side elevation of the improved toilet attachment showing the same in its normal position at which time the 45 cover of the seat is in a closed position.

Fig. 2 is a top plan of the attachment.

Fig. 3 is a side elevation of the attachment showing the seat cover in a partially raised position at which time the manually 50 operated lever is in engagement with the flushing pawl.

Fig. 4 is a side elevation of the device showing the cover in a raised or opened position, and

Fig. 5 is a detail perspective view of a toilet paper holding plate which is attached

to the standards that pivotally support the manually operated lever.

Referring more particularly to the drawings, 1 designates an ordinary closet bowl 60 of the type which is flushed from a flushing tank 2 by the operation of a rod or chain as indicated at 3. The flushing mechanism is the ordinary construction employed in water closets or toilets and a rod is preferably employed in lieu of the chain or cord, however, the chain or cord may be employed without departing from the spirit of this invention. The bowl 2 has the usual type 65 of seat 4 and cover 5 which forms a closure 70 for the opening in the seat 4 when the cover is in a lowered position.

A standard 6 is supported alongside of the bowl 1, and this standard has a hand lever 7 pivotally connected thereto as shown at 8. 75 The hand lever 7 has a bar 9 pivotally connected to its rear end as shown at 10 and the bar 9 is also pivotally connected as shown at 11 to the cover 5 forwardly of the hinge or pivot 12 of the cover. 80

A spring 13 is connected to the hand lever 7 forwardly of its pivot 8 and to the standard 6. When the cover is in its closed or normal position, as shown in Fig. 1 of the drawings, the outer or forward end 14 of the hand lever 7 is moved downwardly, which 85 raises the rear end of the lever, moving upwardly upon the bar 9 and raising the cover 5 into an open position as shown in Fig. 4 of the drawings. During the upward movement of the rear end of the lever 7 and of the seat 5, the rear end of the lever rides over the beveled end 15 of the flushing pawl 16. The flushing pawl 16 is pivotally mounted as shown at 17, to the tank or 90 casing 2, the lever 7 moving the pawl 16 upwardly in an idle movement. When it is desired to lower the cover 5, the forward end 14 of the lever 7 is moved upwardly which lowers the rear end of the same. In 95 the downward movement of the rear end of the lever 7, the rear terminal thereof will strike the pawl 16 and move the pawl downwardly. The pawl 16 normally engages a pin 18 which is carried by the flushing rod 100 3 so that the downward movement of the pawl 16 will operate or move downwardly the flushing rod 3, and operate the flushing mechanism to flush the bowl simultaneously with the lowering of the seat 5 into its closed 110 position.

A plate 20 is mounted upon the upper

end of the standard 6. The said plate 20 is provided with a recess extending upwardly therein from its lower end, as indicated in dotted lines at 21 in Fig. 5 of the drawings. 5 A toilet paper rack 22 of any ordinary construction is carried by the plate 20 and this rack supports a roll of toilet paper as indicated at 23.

It is to be understood that the lever construction illustrated in the drawings and heretofore described may be duplicated upon each side of the bowl 1 if it is so desired without departing from the spirit of this invention. 10

15 The spring 13 facilitates the downward movement of the outer end of the lever 14 by assisting the pressure applied thereto to lower this end of the lever.

From the foregoing description taken in connection with the accompanying drawings the advantages of construction and the method of operation of the improved flushing and cover operating mechanism for toilets will be readily apparent to those skilled 20 in the art to which this invention appertains and, while in the foregoing description, the principle of the operation of this invention has been described together with various features of construction, it is to be understood 25 that certain minor features of construction, combination and arrangement of parts may be altered to suit practical conditions provided such alterations are comprehended 30 within the scope of what is claimed.

35 What is claimed is:

1. In a device as set forth, the combination with an ordinary water closet bowl including a hinged cover, of a standard supported along side of said bowl, a hand lever 40 pivotally connected intermediate its ends to said standard and lying in a plane above the bowl and cover, a bar pivotally connected to the inner end of said hand lever and pivotally connected to said cover a short 45 distance forwardly of the hinge of the cover for raising and lowering the cover upon pivotal movement of the hand lever, an ordinary flushing mechanism for said bowl, and means operated by the inner end of said 50 lever during the pivotal movement thereof to move said cover into a closed position for operating said flushing mechanism.

2. In a device as set forth, the combination

with an ordinary closet bowl, a hinged cover therefor, a flushing mechanism for flushing said bowl including an operating rod, of a pivoted hand lever, means connecting said hand lever and said cover for raising and lowering the cover upon operation of the hand lever, a pin carried by said flushing 55 mechanism operating rod, a pivoted pawl arranged in the path of the inner end of said lever and normally engaging said pin, whereby upon movement of said lever to lower the cover the pawl will be actuated and cause 60 the same to move said operating mechanism. 65

3. In a device as set forth, the combination with an ordinary water closet bowl, a hinged cover for said bowl, a flushing mechanism for flushing said bowl including an operating rod, of a pin carried by said operating 70 rod, a hand lever pivotally mounted intermediate its ends above said cover, a bar pivotally connected to the inner end of said hand lever and pivotally connected to said 75 cover forwardly of the hinges of the cover, a pawl arranged in the path of the inner end of the hand lever and normally engaging said pin, whereby upon movement of said hand lever to lower said cover, the pawl 80 will be actuated to cause the same to move said flushing mechanism operating rod downward to operate the flushing mechanism. 85

4. In a device as set forth, the combination with an ordinary water closet bowl, a hinged cover for said bowl, a flushing mechanism for flushing said bowl including an operating rod, of a pin carried by said operating 90 rod, a hand lever pivotally mounted intermediate its ends above said bowl, a bar pivotally connected to the inner end of said hand lever and pivotally connected to said seat forwardly of the hinges of the cover, a pivoted pawl arranged in the path of the 95 inner end of the hand lever and normally engaging said pin, a standard for supporting said lever, and a spring connected to said standard and said lever, as and for the purpose specified. 100

In testimony whereof I affix my signature in presence of two witnesses.

PETER H. SAGER
